UNITED STATES PATENT OFFICE

2,439,837

BRUSH RECEPTACLE AND SUSPENDING
BRACKET

Bertram H. Wilcox, Redwood City, Calif.

Application July 13, 1945, Serial No. 604,793

1 Claim. (Cl. 206—15.1)

1

The herein disclosed invention has for its object to provide a brush container for holding a toilet brush off the floor and out of sight.

Another object of my invention is to provide a container for a brush and means whereby the same is suspended from the rear of a toilet seat.

A further object of the invention is to provide a hanger fixedly connected to a toilet seat in combination with a container hooked to but quickly removable from the hanger.

Other features and advantages will become more readily apparent from the following description and the accompanying illustrative drawings in which:

Figure 1 is a broken away rear elevational view of a toilet seat embracing my invention,

Figure 2 is a side elevational view thereof,

Figure 3 is an end view of a hanger member, and

Figure 4 is a perspective view of a container.

In the accompanying drawings as above enumerated and in the following specification, the number 10 indicates my invention which consists of a container for a toilet cleansing brush (not shown) which container comprises side walls 11 and 12 terminating in an integral bridge 13, which extends from the upper edges 14 and 15 of the arcuate upper portions 16 and 17 of said side walls. The container also includes end walls 18 and 19, the former terminating in an elongated channel 20 projecting somewhat upwardly from the said wall 18, which channel is adapted to receive the handle of the brush to be held in the container.

For supporting the container 11 above the floor, I provide a hanger 21 having a horizontal end 22 with an aperture through which the bolt 23 of hinge 24 of the toilet seat and cover projects and which end is held to the bolt by the nut 25. The vertical arm 26 of member 21 has its lower end formed U-shaped as at 27 providing the spaced arms 28 and 29 between which the bridge 13 of member 11 is adapted to slidably seat. In order to secure members 11 and 21 together I provide aligning bores 30 in the said arms 28 and 29, and similar bores 31 in the horizontal portion 32 of the bridge 13, and a pin 33 adapted to project through an aligning series of said bores to hold container 11, to prevent accidental displacement of the hanger when sweeping or cleaning around the toilet bowl 34.

As brushes, and sometimes pumps, must be

2

kept near the toilet and as these articles are unsightly and in the way of sweeping, my above described invention will not only keep them out of sight but out of the way of a broom when sweeping and save time in moving them about. It is obvious that a disinfectant and deodorant may be kept in the container.

It is thought that persons skilled in the art to which the invention relates will be able to obtain 10 a clear understanding of the invention after considering the description in connection with the drawings. Therefore, a more lengthy description is regarded as unnecessary.

Changes in shape, size and rearrangement of 15 details and parts such as come within the purview of the invention claimed may be resorted to, in actual practice, if desired.

Having now described my invention that which I claim as new and desire to procure by Letters 20 Patent is:

A device of the character described comprising 25 a U-shaped hanger having attaching means on its upper end and spaced integral horizontally extending parallel supporting arms on its lower end, a brush holding container including a bail handle portion slidably and adjustably disposed between said spaced parallel supporting arms, means extending through said bail handle and parallel arms for securing the same in adjusted 30 position, and an inclined arcuate brush handle supporting trough formed on said brush holding container extending laterally therefrom.

BERTRAM H. WILCOX.
